UNITED STATES PATENT OFFICE.

EDWARD HEYDON, OF INDIANAPOLIS, INDIANA.

CROSS-ARM SUPPORT FOR POLES.

1,316,952.

Specification of Letters Patent. Patented Sept. 23, 1919.

Application filed April 18, 1919. Serial No. 291,110.

To all whom it may concern:

Be it known that I, EDWARD HEYDON, a citizen of the United States, residing at Indianapolis, in the county of Marion and State of Indiana, have invented a new and useful Cross-Arm Support for Poles, of which the following is a specification.

It is the object of my invention to provide a cross-arm support for poles, as for 10 telegraph, telephone, and transmission lines, which will not require any notching of the poles with its consequent weakening and rot-producing, which can be applied quickly and easily, and which is simple and inexpensive 15 to manufacture.

The accompanying drawing illustrates my invention: Figure 1 is a perspective view of a cross-arm support embodying my invention, as seen from the pole side; Fig. 2 20 is a perspective view of the same cross-arm support as seen from the cross-arm side; and Fig. 3 is a horizontal section through such cross-arm support, showing in dotted lines the associated pole, cross-arm, and attaching bolt.

The cross-arm support comprises two overlapping plates 10 and 11, which plates are preferably provided with vertical corrugations 12 on their adjacent faces so as 30 to prevent them from relative slipping when they are clamped in operative position. One of the overlapping plates, in this case the plate 11, is provided with guide lugs 13 which extend through slots 14 in the other 35 plate, here the plate 10; and these guide lugs 13 are preferably headed or peened so as to prevent the two plates from being separated after they have once been put together while still permitting relative sliding of the 40 plates upon each other. Each of the plates 10 and 11 carries at one horizontal end a pair of fingers 15, which are at opposite ends of the respective plates; and these fingers are arranged to extend part way around the 45 associated pole 16, and are provided at their ends with lateral prongs 17 projecting toward the pole so that they may be driven into the pole by hammer blows, as is clear from Fig. 3. On the opposite sides of the 50 plates 10 and 11 from that from which the fingers 15 project such plates are provided at their lower edges with shelves 18, on which the cross-arm 19 may rest. The cross-arm bears against the outer face of the plate 55 11, and also preferably against a short face

20, preferably horizontally corrugated, on a thickened portion of the plate 10 at that end of such plate from which the fingers 15 project, so that the cross-arm will have as wide a bearing as possible. The parts are 60 fastened together by a fastening bolt 21, which passes through registering holes in the pole 16 and cross-arm 19 and through central horizontal slots 22 in the plates 10 and 11. 65

In mounting a cross-arm on the pole with my improved cross-arm support, the parts are all fastened together by the single bolt 21. The cross-arm rests on the shelves 18 and is thereby prevented from turning about 70 the bolt 21 as an axis just as fully as though it were set into a notch in the pole, but yet the pole itself is not notched so that it is not weakened and is not as subject to rotting as it would be if it were notched, 75 for when such notches are provided water collects and stands in them and causes rotting. Thus both the strength and the life of the pole are increased.

I claim as my invention:

1. A cross-arm support for poles, comprising two overlapping plates vertically corrugated on their adjacent faces and provided with pole-gripping fingers which are brought into engagement with the pole by 85 relative sliding of the two plates, said two plates being provided with slots through which a bolt may be passed to clamp the two plates together between a cross-arm on one side and the pole on the other. 90

2. A cross-arm support for poles, comprising two overlapping plates provided with pole-gripping fingers which are brought into engagement with the pole by relative sliding of the two plates, said two plates being 95 provided with slots through which a bolt may be passed to clamp the two plates together between a cross-arm on one side and the pole on the other.

3. A cross-arm support for poles, comprising two overlapping plates provided with pole-gripping fingers which are brought into engagement with the pole by relative sliding of the two plates, said two plates being 100 provided with slots through which a bolt may be passed to clamp the two plates together between a cross-arm on one side and the pole on the other, said pole-gripping fingers being 105 provided with lateral prongs which may be driven into the pole. 110

4. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, said plates being provided on their cross-arm-engaging faces with shelves which project beneath the cross-arm.
5. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, one of said plates being provided with guide lugs which project into guide slots in the other, said guide lugs being headed to prevent separation of the two plates.
- 15 6. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, and a part projecting from a plate over one of the horizontal faces of the cross-arm.
- 20 7. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, one of said plates being provided with guide lugs which project into guide slots in the other.
- 25 8. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, one of said plates being provided with guide lugs which project into guide slots in the other.

9. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, preventing turning of the cross-arm about such bolt.

10 11. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, one of said plates being provided with guide lugs which project into guide slots in the other, said guide lugs being headed to prevent separation of the two plates.

15 12. A cross-arm support for poles, comprising two overlapping plates provided with pole-gripping fingers which are brought into engagement with the pole by relative sliding of the two plates, said two plates being provided with slots through which a bolt may be passed to clamp the two plates together between a cross-arm on one side and the pole on the other, one of said plates being provided with guide lugs which project into guide slots in the other.

13. In witness whereof I have hereunto set my hand at Indianapolis, Indiana, this sixteenth day of April, A. D., one thousand nine hundred and nineteen.

EDWARD HEYDON.
